UNITED STATES PATENT OFFICE

ALBERT M. CARDER, OF NEWTON, IOWA, ASSIGNOR OF ONE-HALF TO MARY JANE CARDER, OF NEWTON, IOWA

REVERSIBLE CONTROL FOR HOT AND COLD AIR IN FURNACES

Application filed April 30, 1931. Serial No. 533,913.

This invention relates to air circulating means employed in connection with heating units such as warm air furnaces and related devices, and has as an object the provision of improved means for circulating the air passing through such heating units.

A further object of the invention is to be found in the improved construction of air circulating means adaptable to warm air furnaces and the like, which improved construction permits of ready adaptation of the invention to conventional heater installations.

A further object of the invention resides in the reversible and adjustable character of the air circulating means, whereby the adaptability of the improvement is enhanced and its functional advantage increased.

A further object of the invention is to provide improved air circulating means operable in conjunction with a warm air heater for either heating or cooling effect.

A further object of the invention is to provide improved air circulating means of the character described which is simple of manufacture and installation, readily accessible for adjustment, service and repair, efficient in operation, free from objectionable noise and vibration, and durable in use.

My invention consists in the construction, arrangement and combination of elements hereinafter set forth, pointed out in the claims and illustrated by the accompanying drawings, in which—

Figure 1 is a front elevation of a conventionalized warm air heater whereon one form of my invention has been mounted for practical use. Figure 2 is a front elevation of a conventionalized warm air heater differing slightly in construction from the showing of Figure 1 whereon a modified form of the invention has been mounted for practical use. Figure 3 is a cross section, on an enlarged scale, taken on the indicated line 3—3 of Figure 1. Figure 4 is a vertical section through the elements shown in Figure 3 taken on the line 4—4 of said latter figure. Figure 5 is a cross section on the same scale as Figures 3 and 4 taken on the indicated line 5—5 of Figure 2. Figure 6 is another view of the elements shown in Figure 5 taken at right

angles to the showing of the latter figure. Figure 7 is an isometric view, on a further enlarged scale, of the removable assembly illustrated in Figures 2, 5 and 6, the fan assembly being omitted. Figure 8 is an isometric view on the same scale as Figure 7 of the removable assembly illustrated in Figures 1, 3 and 4, the fan assembly being omitted. Figure 9 is a conventionalized wiring diagram showing a preferred method of connecting the fan motors for operation.

In the construction of my improvement as shown, a warm air heater is conventionally represented in Figures 1 and 2 as comprising a heater 10 suitably arranged for operation with any desired fuel enclosed by and sealed into a warm air jacket 11 in a common and well known manner. From the dome or upper portion of the jacket 11, pipes or conduits 12 extend to suitable discharge openings in the rooms or apartments to be heated and similar pipes or conduits 13, preferably two in number, connect the rooms and apartments to be heated with the lower portion of the jacket 11, so that, when the heater 10 is operated, the warmer air within the jacket 11 rises through and escapes from the pipes 12 into the rooms and apartments, heating them, and cooler air from said rooms and apartments is drawn through the pipes 13 and into the jacket 11 where it is heated sufficiently to continue the cycle of circulation. Air circulation initiated and maintained by thermal differences in the manner described is not highly efficient in a heating system. The system described is necessarily sluggish, wasteful of fuel, difficult of accurate control, uneven in its distribution of heat, and, because of the high temperatures required for adequate heating, destructive of the heater; to overcome which inefficiencies the instant invention has been designed for adaptation to existing installations.

In the embodiment of the invention illustrated in Figures 1, 3, 4 and 8, a preferred form readily mountable on the majority of warm air heater installations is shown, this preferred type of the invention being particularly designed for use with heaters of the type wherein the cold air pipes 13 are

connected with the heater jacket 11 by means of elbows 14, as illustrated in Figure 1. As illustrated in the figures above noted, rectangular apertures of suitable size are 5 formed in the pipes 13, one aperture for each of said pipes, the location of an aperture relative to its pipe being determined solely by convenience and accessibility, and closure members are provided for said apertures and 10 arranged for removable and reversible mounting relative thereto. Each of the closure members comprises a cover plate 15, preferably of sheet metal, of a size sufficient to overlap all four margins of its aperture 15 and curved to conform to and lie closely against the outer surface of a pipe 13, and a block 16, of more rigid material, secured centrally of and curved to fit snugly against the concave side of the plate 15, said block 16 being of a size to just fill the aperture formed in the pipe 13. A gasket 17, of felt, cork, or similar material, is positioned against the projecting margins of the plate 15 about the block 16, which gasket engages 20 against the outer surface of the pipe 13 when the closure member is in place thereon and serves to adequately seal the opening in said pipe. Any suitable means may be employed to hold the closure member in place on the 25 pipe 13, one such means being illustrated as comprising a groove formed by a suitably shaped strip of metal 18 adjacent the lower margin of the aperture and in which the lower margin of the plate 15 is received and 30 a pivoted clip 19 carried by the pipe 13 in position to be swung into engaging and holding relation with the upper margin of said plate 15, said clip 19 being perhaps unnecessary, since the unbalanced weight of the 35 devices carried by the closure member is sufficient to hold the upper portion of said member in position when the lower portion thereof is held against displacement radially of the pipe. The closure member formed as 40 above described is symmetrical about its transverse axis and hence may be mounted on a pipe 13 in either of two positions, thus being reversible relative to said pipe, and a handle 20 is fixed to the outer surface of 45 the plate 15 to facilitate handling of the closure member. Fixed to and projecting radially inwardly from the inner surface 50 of the block 16, a rigid bracket 21 provides a support for an electric motor 22 carrying 55 a suitable fan 23 on its driven shaft. The connection between the motor 22 and bracket 21 may be had in any manner desired, but 60 should preferably provide for adjustment of said motor in the axial plane of the pipe 13, to which end I illustrate a U-shaped bracket 24 carried by the motor housing and arranged to telescopically embrace the inner 65 end of the bracket 21, a bolt 25 adjustably interconnecting said brackets.

65 In Figure 2 is illustrated a modified con-

struction of warm air heater, similar in all essential respects to the showing of Figure 1 and having the elements 10, 11, 12 and 13 previously described, but differing from the showing of Figure 1 in that the cold air 70 pipes 13 are connected with the jacket 11 by means of boots or boxes 14' instead of the elbows 14, which difference requires modification of the previously described invention to adapt it to the altered heater. While it 75 would be possible to mount the closure plate and fan assembly in the pipes 13 of Figure 2 in the manner previously described, such an arrangement would have limited efficiency in that the angular construction of the boots 80 14' and their angular relation with the pipes 13 would not be conducive to smooth flow of air therethrough and the eddies set up by air currents therein would prove disadvantageous. The more efficient arrangement involves 85 mounting of the fan and closure plate assembly in a boot 14', and modifying the assembly to minimize eddy currents as hereinafter described. As shown in Figures 2, 5, 6 and 7 of the drawings, suitable apertures are 90 formed in plane side portions of the boots 14' and closure members composed of elements 15', 16' and 17', identical with the elements 15, 16 and 17 save for the curved construction of the latter and interrelated as are said 95 latter elements, are mounted in closing relation with said apertures and suitably retained in such relation, a bracket strip 18' similar to and functioning in the same manner as the strip 18 providing a simple and convenient 100 positioning element. A relatively short tubular element 26 is mounted on and spaced inwardly from the closure member 15', 16', 17', and so arranged as to position its axis in substantial alinement with the normal air 105 flow through a boot 14', the bolt 27, brace 28 and nuts 29 providing a simple and adequate connection between the closure member and element 26 and affording means whereby the 110 axis position of said element may be varied. Fixed to the inner surface of the tubular element 26 and projecting inwardly and radially therefrom a bracket 21', similar to the bracket 21, provides a mounting for the motor 22 carrying its fan 23, the connections between the fan motor and bracket 21' being 115 identical with those previously described. A suitable handle 20' is formed on or fixed to the outer end of the bolt 27 to facilitate handling of the closure member and its attached 120 elements.

The fan motors 22 may be operatively connected with a source of electrical energy in any manner suitable to a given installation, and may be arranged for either manual or 125 automatic control, the latter being diagrammatically illustrated in Figures 1, 2 and 9. In these latter figures an automatic control element 30 is shown conventionally, which control element may be either time or tem- 130

perature operated, the motors 22 being connected in parallel through the element 30 and a line switch 31 with a power line 32. The element 30 may of course be dispensed with 5 and the motors controlled directly by the line switch, the only essential being that the motors be connected and arranged for simultaneous operation.

In the practical operation of the improvement, the elements being assembled, connected and arranged as shown in Figures 1 and 2, closing of the circuits to the motors 22 actuates the fans 23, thereby establishing a positive flow of air downwardly through the 15 pipes 13, through the jacket 11 about the heater 10, and outwardly through the pipes 12, thus insuring a circulation of warm air throughout the rooms and apartments to be heated and enhancing the efficiency of the 20 heating plant. In hot weather, the positions of the fans may be reversed and they may be operated to draw warm air from the rooms and apartments through the jacket 11 for return to the rooms and apartments, which 25 action, due to the usual location of the heating plant in a cellar or basement, has a pronounced cooling effect.

It is to be noted that my construction of closure members and fan mountings renders 30 the invention almost if not entirely universally adaptable to warm air heater installations with minimum expense and effort, and the use of a fan element in each of the cold air pipes prevents back pressure or air lock in 35 any part of the circulation system.

Since changes and modifications in the specific form, construction and arrangement of the elements illustrated and described may be had without departing from the spirit of 40 the invention, I wish to be understood as being limited solely by the scope of the appended claims rather than by any details of the illustrative showing and foregoing description.

45 I claim as my invention—

1. In a heating system having an air conduit, an aperture in a wall of said conduit, a supporting step adjacent the lower margin of said aperture, a closure plate supported 50 by said step in closing relation with said aperture and an electric fan mounted on said plate in operative relation within said conduit.

2. In a heating system having an air conduit, an aperture in a vertical wall of said conduit, a supporting step adjacent the lower margin of said aperture, a closure plate supported by said step in marginally overlapping relation with said aperture and an electric fan mounted on said plate in operative relation within said conduit, the offset weight 60 of said fan acting to position and hold said plate in closing relation with said aperture.

3. In a heating system having an air conduit, an aperture in a vertical wall of said

conduit, a channeled supporting step adjacent the lower margin of said aperture, a closure plate mounted with its lower margin in said step and positioned in marginally overlapping relation with said aperture, cushioning means between the overlapping portions of said plate and conduit, and an electric fan adjustably mounted on said plate in operative relation within said conduit, the offset weight 70 of said fan acting to position and hold said plate in closing relation with said aperture. 75

4. In a heating system having an air conduit, an aperture in a vertical wall of said conduit, a channeled supporting step adjacent the lower margin of said aperture, a closure plate mounted with its lower margin in said step and positioned in marginally overlapping relation with said aperture, an offset on the inner side of said plate arranged to engage within and substantially fill said aperture, cushioning and sealing means between the overlapping portions of said plate and conduit, and an electric fan mounted on said plate in operative relation within said conduit, the offset weight of said fan acting to 80 position and hold said plate in closing relation with said aperture. 85

5. In a heating system having an air conduit, an aperture in a vertical wall of said conduit, a channeled supporting step adjacent the lower margin of said aperture, a closure plate mounted with its lower margin in said step and positioned in marginally overlapping relation with said aperture, a relatively short, supplemental conduit adjustably secured to said plate for positioning 90 within said first conduit, and an electric fan adjustably mounted in operative relation within said supplemental conduit, the offset weight of said supplemental conduit and fan 95 acting to position and hold said plate in closing relation with said aperture. 100

In witness whereof I affix my signature.
ALBERT M. CARDER.
